UNITED STATES PATENT OFFICE.

WALTHER FELD, OF HÖNNINGEN-ON-THE-RHINE, GERMANY, ASSIGNOR TO
THE AMERICAN SUGAR REFINING COMPANY, OF NEW YORK, N. Y.

PROCESS OF EXTRACTING SUGAR.

SPECIFICATION forming part of Letters Patent No. 592,518, dated October 26, 1897.

Application filed August 18, 1896. Serial No. 603,105. (No specimens.)

To all whom it may concern:

Be it known that I, WALTHER FELD, a subject of the German Emperor, residing at Hönningen-on-the-Rhine, of Rhine Province, German Empire, have invented certain new and useful Improvements in Processes of Extracting Sugar from Molasses and other Saccharine Liquors by the Use of Barium Hydroxisulfid, of which the following is a specification.

10 It has heretofore been proposed to extract sugar from molasses or other sacchariferous liquors or juices by the use of barium compounds obtained from barium sulfid, (BaS.) The barium sulfid is obtained by the reduction 15 of commercial heavy spar or barium sulfate with coal. It is the fact that when barium sulfid is leached systematically with hot water it gives a solution of barium hydroxisulfid, (BaS+H₂O=BaSHOH,) a substance 20 which is very soluble in hot water, but will crystallize easily from the solution if cooled down to ordinary atmospheric temperature. The authorities have not hitherto accepted this fact; but for the purposes of the present 25 case the matter is not important, because any chemist may theoretically explain the chemical reactions differently, and can, as herein-after illustrated, easily substitute other formulas for those herein given. In any event 30 the practical result will be the same.

In the process of extracting sugar from molasses as heretofore practiced a solution supposedly of barium sulfid, but actually containing about thirty-five per cent. to forty per 35 cent. of barium hydroxisulfid and having a temperature of about 145° Fahrenheit, is thoroughly mixed with molasses or other sacchariferous liquor in such proportions that the mixture will contain for each one hundred 40 parts of sugar about one hundred and fifteen parts of barium hydroxisulfid. Theoretically this is about five per cent. more barium hydroxisulfid than is necessary, but it is advisable to use a small excess, and if the molasses 45 contains glucose or invert sugar a proportionally larger amount must be added—thus for one part of glucose about one part of barium hydroxisulfid. This excess reacts upon the glucose and transforms it into barium compounds. By the reaction of the sugar the

barium hydroxisulfid is split into barium oxid, which by combining with the sugar forms insoluble barium saccharate, and into water and barium hydrosulfid, which remains dissolved in the waste lye, according to the 55 formula:

This reaction takes place at all temperatures, but in order to accelerate it and have 60 a complete precipitation of the saccharate it is usual to heat the mixture above 140° Fahrenheit. By filtration through filter-presses and washing with water in the usual manner the barium saccharate is separated from the 65 waste lye, which contains, besides the impurities originally present in the molasses, the whole quantity of barium hydrosulfid formed by the process, the excess of barium hydroxisulfid used, and in lesser quantity various 70 barium salts formed by the reaction of the barium hydroxisulfid upon the glucose and other impurities of the molasses.

The present invention consists in the hereinafter-described method of extracting sugar 75 from molasses or other sacchariferous liquors by the use of barium compounds in such manner as to effect the economical recovery of the barium and sulfur employed.

The present invention is a modification of 80 that set forth in my pending application, Serial No. 586,435, describing a method of so conducting the extraction of sugar from molasses or other sacchariferous liquors by the use of barium compounds as to insure the recovery of the barium and sulfur employed. In the process described in the said application the waste lye remaining after the formation and removal of the barium saccharate therefrom is saturated with carbonic acid in 85 order to transform all the sulfur present in it into hydrogen sulfid, which by subsequent burning with air is made to yield sulfurous acid. In order that the hydrogen sulfid may easily be made to thus yield sulfurous acid, 90 it is essential that the carbonic-acid gas employed shall contain a high percentage of pure carbonic acid—as, say, thirty to forty per cent. The necessity for using carbonic gas containing such a high percentage of pure 95 100

carbonic acid is, by the present invention, avoided by first treating the waste lye either with magnesium sulfate or with magnesium sulfite, which, for the purposes of the present invention, are the equivalents of each other, it being, of course, understood that they are used not only to set free the hydrogen sulfid from the waste lye, but also to furnish the sulfuric acid, which, by combination with the barium present, will ultimately form either barium sulfate or barium sulfite, according to which of the said magnesium salts is employed. In carrying out the process there is mixed with the waste lye such quantity of the magnesium salt employed as will suffice to decompose the barium compounds present and transform the barium into barium sulfate or barium sulfite, as the case may be. The magnesium salt may be either in solution or in the form of a solid salt. The magnesium salt having been introduced into the waste lye, the mixture is boiled until all the sulfur previously combined with the barium is set free in the form of gaseous hydrogen sulfid, which is conducted off to a gasometer, while there is concurrently formed in the waste lye insoluble barium sulfate or barium sulfite, as the case may be, and magnesium hydrate. For illustration, if magnesium sulfite is employed the result will be as indicated in the following formula:

The next step is to transform the magnesium hydrate into magnesium carbonate by introducing into the mixture sufficient carbonic-acid gas to effect such transformation, and for this purpose there can be used gas containing only a small percentage of carbon acid—as, for example, fuel-gas. The resulting magnesium carbonate, together with the barium sulfite, after having been separated from the waste lye, which is afforded by the use of the ordinary filter-presses, is mixed with water and then treated either with sulfurous acid, whereby the magnesium carbonate will be transformed into soluble magnesium sulfite, or with sulfuric acid, which will transform the magnesium carbonate into magnesium sulfate, while in either case the carbonic acid is set free. The barium sulfite is then separated by the use of the ordinary filter-press. The object of the sulfur-acid treatment is simply to transform the magnesium carbonate into a salt—to wit, magnesium sulfate or magnesium sulfite—which is adapted for use in a repetition of the described process of extracting sugar from another lot of molasses or other sacchariferous liquor. As a matter of economy it is preferred to use sulfurous acid, because the hydrogen sulfid which has been collected in the earlier stages of the process can with little cost be made to yield sulfurous acid by the ordinary process of burning it with air in a suitable chamber.

The separation of the sugar from the barium saccharate is effected by heating it with a solution of magnesium sulfite or magnesium sulfate, thus forming an aqueous solution of sugar mixed with insoluble barium sulfite or barium sulfate and magnesium hydrate. This mixture is then treated with carbonic-acid gas until the magnesium hydrate is transformed into magnesium carbonate, which, together with the barium salts, is then separated by filter-presses. The remaining pure-sugar solution is then evaporated in the usual way to obtain the crystallizable sugar therefrom.

The barium salt and the magnesium carbonate are then mixed with water and treated with a sulfur acid, and the magnesium carbonate is thus transformed into a soluble magnesium salt susceptible of use in a repetition of the described process. Finally the barium salts obtained, as described, from the waste lye and by the decomposition of the barium saccharate are mixed with coal and heated in a reverberatory furnace in the usual manner, and are thus transformed into barium sulfid, which may be again used, as herein set forth.

It will be perceived that for the purposes of the different steps in the present process, in which they are respectively employed, magnesium sulfate and magnesium sulfite are equivalents of each other, and also that sulfuric acid and sulfurous acid are equivalents of each other.

What is claimed as the invention is—

1. In processes for extracting sugar from molasses or other sacchariferous liquors by the use of barium compounds, the method of recovering from the waste lye the sulfur introduced in combination with barium, which consists in adding to the waste lye a sulfur salt of magnesium, then boiling the waste lye and collecting the thereby-developed gaseous hydrogen sulfid, and burning the same to sulfurous acid, substantially as described.

2. In processes for extracting sugar from molasses or other sacchariferous liquors by the use of barium compounds the method of recovering the barium from the waste lye, which consists in first boiling the waste lye with a sulfur salt of magnesium; secondly, saturating it with carbonic acid; thirdly, separating the resulting precipitate from the solution by filter-presses; fourthly, mixing said precipitate with water; fifthly, saturating the resulting mixture with a sulfur acid; sixthly, separating the resulting barium salt from said mixture by filtration, and, finally, mixing such barium salt with coal and reducing it in a reverberatory furnace to barium sulfid, substantially as described.

3. In processes for extracting sugar from molasses or other sacchariferous liquors by the use of barium compounds, whereby barium saccharate is formed, the method of recovering the barium which consists in first

heating the barium saccharate with a sulfur salt of magnesium; secondly, saturating it with carbonic acid; thirdly, separating the precipitate from the solution; fourthly, mixing said precipitate with water; fifthly, saturating the resulting mixture with a sulfur acid; sixthly, separating the resulting barium salt from the mixture, and, finally, mixing such barium salt with coal and reducing it in a reverberatory furnace to barium sulfid, substantially as described.

4. The process of extracting sugar from molasses or other sacchariferous liquors by the use of barium compounds, as herein described, whereby the constituents of the compounds employed are recovered in suitable form for repeated use, which consists in treating a saccharine liquor with barium hydroxide sulfid, thus forming barium saccharate; separating the barium saccharate from the waste lye; heating the barium saccharate with a sulfur salt of magnesium and treating it with carbonic acid; separating the resulting sulfur

salt of barium and the resulting magnesium carbonate from the remaining pure-sugar solution; heating the waste lye with a sulfur salt of magnesium; collecting the thereby-developed hydrogen sulfid and burning it to sulfuric acid; then treating the waste lye with carbonic acid; separating the resulting magnesium carbonate and sulfur salt of barium; treating said magnesium carbonate and sulfur salt of barium with a sulfur acid, preferably with the sulfurous acid yielded by the burning of the hydrogen sulfid, thereby producing a soluble sulfur salt of magnesium; separating the sulfur salt of barium, and, finally, reducing the thus-obtained barium salts to barium sulfid, substantially as set forth.

In testimony whereof I have affixed my signature in presence of two witnesses.

WALTHER FELD.
